UNITED STATES PATENT OFFICE.

FRANCIS C. OSBORN, OF DETROIT, MICHIGAN.

TUBE-MAKING MACHINE.

SPECIFICATION forming part of Letters Patent No. 710,507, dated October 7, 1902.

Application filed March 19, 1902. Serial No. 98,918. (No model.)

To all whom it may concern:

Be it known that I, FRANCIS C. OSBORN, a citizen of the United States, residing at 223 Putnam avenue, in the city of Detroit, county 5 of Wayne, and State of Michigan, have invented certain new and useful Improvements in Tube-Making Machines, of which the following is a specification.

This invention relates to improvements in 10 machines for manufacturing continuous spirally-wound tubing of paper or other material, and more specifically to that class of machines in which the strips of material are carried spirally around a stationary mandrel 15 and moved continuously forward toward the end of the mandrel by a belt or belts wrapped about the material and mandrel and driven in the proper direction and at the proper angle to wind the strips into a tube in which the 20 strips may be joined either with overlapping or abutting edges and with the layers arranged with broken joints.

My improvements consist in an improved 25 driving mechanism and other improvements, all of which will be more specifically pointed out in the claims.

In the drawings, Figure 1 is a plan view of the machine. Fig. 2 is a top view of mandrel, strips of material, and belt. Fig. 3 30 shows paste apparatus in section. Fig. 4 is a belt-driving pulley in side elevation, showing gearing and belt-tightener slide. Fig. 5 is a belt-driving pulley in elevation, showing 35 gearing and connection with main shaft; Fig. 6, a top view of Fig. 5. Fig. 7 shows belt-guide.

The mechanism is mounted upon a base or bed A similar to a lathe-bed. The main driving-shaft B is mounted in brackets b at 40 one side of the base and may be driven by a large pulley mounted directly upon it or by a smaller pulley and gearing, as shown in the drawings, in which the power is transmitted from the cone-pulley C through the back 45 gearing and the intermediate gear to the shaft, as is clearly shown in Fig. 1. The mandrel M, held in a fixed position by inserting one end in a socket of the headpiece of the bed, is mounted centrally on the bed and 50 sufficiently far above it to bring it in the horizontal plane of the belt-driving pulleys p p'.

The belt-driving pulleys p p', of which there

may be one or more pairs, are keyed upon vertical stud-shafts s, mounted in bracket-bearings s'. The lower ends of these stud-shafts are fitted with bevel-gears G, arranged to mesh with bevel-gears g g². The gear g on the side on which the main driving-shaft B is located is mounted on the driving-shaft and is driven thereby. The bevel-gear g² on 60 the opposite side of the machine is driven by a shaft s³, mounted on the swinging bed-piece S and driven through the gear g, meshing with the gear G. The number of teeth of these several gears is such that the belt- 65 driving pulleys are all driven at the same speed. A sliding bed-piece S' is arranged to be moved along the ways of the bed, and upon this is mounted a swinging bed-piece S, pivoted to the sliding bed-piece at or near its 70 center. The swinging bed-piece carries the pulleys, stud-shafts, and gearing described above. One of the belt-driven pulleys of each pair (preferably the one on the side opposite the main driving-shaft) is mounted on a slide 75 arranged in the usual manner, with screw and hand-wheel for moving the same for the purpose of changing the distance between the pulleys in order to give proper tension to the belt. (See Figs. 1 and 4.) The main driving- 80 shaft, in addition to the fixed bearings b, has a swinging bearing b², mounted on each of the swinging bed-pieces S. This bearing consists of a bracket-piece pivoted to the swinging bed-piece S, so that it swings concentrically 85 with stud-shaft above it. (See Fig. 5.) The gear g is sleeved in the bearing and is held therein by a collar c³, threaded on the sleeve. The shaft passes through the gear and sleeve and has spline-and-groove connection therewith. The gear g² also has spline-and-groove connection with the shaft s³.

The main shaft is provided with the universal joints J, which permit it to adapt itself to the varying position of the bearings b² when 95 the swinging bed-pieces are moved to change the angle between them and the mandrel. An endless belt T is provided for each pair of pulleys and is mounted thereon, as shown in the drawings, with one turn around the 100 mandrel. The belt should be about the same width as the strips of material to be wound.

One strip of the paper or other material to be wound is fed to the mandrel dry, as shown

at 1. A second strip 2 is fed from the opposite side of the mandrel and provided with paste on one side. The paste may be applied in any suitable manner. The apparatus for 5 applying the paste shown in the drawings consists of a box v , in which is mounted a roller v' , having suitable bearings and provided with a pulley v^2 , which is connected by belt to a pulley v^3 on the main shaft. The 10 paper strip is guided over the roller, carrying the paste under a guide-roll v^4 , over a scraper v^5 , and under second guide-roll v^6 . A hopper v^7 is provided for convenience in supplying the box with paste, and the roll of paper or 15 other material is mounted above the box in suitable brackets.

The strips of material are carefully guided at the point where they pass onto the mandrel by adjustable guides x x' , which are slidably connected to the bed at x^2 . The strips are further guided and forced forward along the mandrel by the extended guide-pieces z z' . Strip 1 is thus guided by the piece z , fast on the mandrel, and strip 2 is guided by piece 25 z' , extending over the surface of the mandrel from the adjustable guide x' .

A third and fourth strip of material may be wound in a manner similar to the winding of strips 1 and 2, in which case similar guides, 30 paste, rolls, &c., would be provided and arranged in connection with the second winding-belt. In this case both the additional strips would need to be provided with paste. It will be obvious that by increasing the number 35 of winding-belts any number of strips may be wound into one tube in this manner.

It being understood that the swinging bed-pieces S are not at all times in parallel relation with only two sets of pulleys and two swinging bed-pieces, as shown in the drawings, it is necessary to employ only two universal joints in the driving-shaft. If additional sets of pulleys mounted on independent swinging bed-pieces are used, a universal joint in 45 the shaft for each of such swinging bed-pieces would be necessary and would be located in the portion of the driving-shaft connecting the bed-pieces shown with such additional bed-pieces.

50 What I claim is—

1. In a tube-forming machine, a mandrel, a continuous winding-belt passing to, over, and around the mandrel, a pair of pulleys for driving the belt mounted upon a swinging element, a main driving-pulley, and a flexible driving-shaft connection between the main driving-pulley and the belt-driving pulleys, substantially as set forth.

2. In a tube-forming machine, a mandrel, a continuous winding-belt passing to, over, and around the mandrel, a pair of pulleys, one on either side of the mandrel, for driving the belt, a swinging bed-piece carrying the pulleys whereby the angle between the mandrel and belt may be varied, a main driving-pulley mounted upon the fixed framework of the machine, and a universally-jointed con-

necting-shaft between the main pulley and the belt-driving pulleys, substantially as set forth. 70

3. In a tube-forming machine, a mandrel, a continuous winding-belt passing to, over, and around the mandrel, a pair of pulleys, one on either side of the mandrel, for driving the belt, a centrally-pivoted swinging bed-piece carrying the pulleys whereby the angle between the mandrel and belt may be varied, a main driving-pulley mounted upon the fixed framework of the machine, and a universally-jointed connecting-shaft between the main 75 pulley and the belt-driving pulleys, substantially as set forth. 80

4. In a tube-forming machine, a mandrel, a continuous winding-belt passing to, over, and around the mandrel, a pair of pulleys, 85 one on either side of the mandrel, for driving the belt, a centrally-pivoted swinging bed-piece carrying the pulleys whereby the angle between the mandrel and belt may be varied, a main driving-pulley mounted upon the fixed 90 framework of the machine, and a main driving-shaft provided with universal joints and having a sliding connection between the main pulley and the belt-driving pulleys, substantially as set forth. 95

5. In a tube-forming machine, a mandrel fixedly mounted, a continuous winding-belt passing to, over, and around the mandrel, a pair of pulleys mounted on vertical stud-shafts, one on either side of the mandrel, for driving the belt, a swinging bed-piece carrying the pulleys whereby the angle between the mandrel and belt may be varied, a main driving-shaft mounted upon the fixed framework of the machine, a universally-jointed 100 connecting-shaft between the main pulley and one of the belt-driving pulleys, and a slide adjustment for one of the belt-driving pulleys whereby the tension of the belt may be varied, substantially as set forth. 105

6. In a tube-forming machine, a stationary mandrel for winding two or more strips of material, a strip-guide z mounted directly on the mandrel, a strip-guide z' adjustably mounted on the framework and extending 115 over the surface of the mandrel, and mechanism for feeding forward the strips, substantially as set forth. 110

7. In a tube-forming machine, a mandrel arranged for winding strips 1 and 2, a strip-guide z mounted directly on the mandrel for guiding one of the strips, a strip-guide z' adjustably mounted on the framework and extending over the surface of the mandrel for guiding the other strip, and mechanism for 125 feeding forward the strips, substantially as set forth. 120

In testimony whereof I have signed my name to this specification in the presence of two subscribing witnesses.

FRANCIS C. OSBORN.
